United States Patent

Des. 234,735
Patented Apr. 8, 1975

234,735

TABLE OR SIMILAR ARTICLE

George W. Podell, Newburgh, N.Y., assignor to Monarch
Metal Products, Inc., New Windsor, N.Y.

Filed Aug. 6, 1973, Ser. No. 385,954

Term of patent 14 years

Int. Cl. D6—03

U.S. Cl. D6—177

FIG. 1

FIG. 2

FIG. 3

FIG. 1 is a front perspective view of a table, showing my new design;

FIG. 2 is a rear elevational view thereof; and

FIG. 3 is a side elevational view thereof.

I claim:

The ornamental design for a table or similar article, substantially as shown.
